UNITED STATES PATENT OFFICE.

JAMES H. WEAVER AND ISAAC R. LAUX, OF WADSWORTH, OHIO, ASSIGNEES
TO OHIO MATCH COMPANY, OF WADSWORTH, OHIO, A CORPORATION
OF OHIO.

MATCH-MAKING MACHINE.

No. 851,848.

Specification of Letters Patent.

Patented April 30, 1907.

Application filed September 12, 1906. Serial No. 334,303.

To all whom it may concern:

Be it known that we, JAMES H. WEAVER and ISAAC R. LAUX, citizens of the United States, residing at Wadsworth, in the county 5 of Medina and State of Ohio, have invented a certain new and useful Improvement in Match-Making Machines, of which the following is a full, clear, and exact description.

The invention relates to that class of machines for making matches wherein an endless chain of plates receives the splints and conducts them from one mechanism to another to complete the matches and discharge them for boxing.

15 The object of the invention is to time or control the travel of the plates in such way that a plate containing finished matches will be arrested over the discharging or punching-out mechanism and the matches discharged 20 row-by-row simultaneously with the stopping of an empty plate over the filling-in mechanism where said plate has splints stuck in it row-by-row. In attaining this object, the punching-out and filling-in mechanisms 25 are relatively so actuated that while the punching-out mechanism on its forward movement is punching out or discharging a row of finished matches, the cutting head on its upward motion serves as a filling-in mechanism and inserts a row of splints. During 30 the time that the punching-out mechanism is about one-third the distance on its backward stroke and the cutting-head is about one-third the distance on its downward stroke, and until they reach two-thirds of 35 their forward and upward strokes respectively, the chain of plates is moved forward the length of the distance between the centers of two adjacent rows of holes in the 40 plates, and this results in bringing the next rows of holes respectively opposite the punching-out and the filling-in mechanisms and securely holding them in these positions until the said mechanisms recede, and these operations are repeated so long as the machine is 45 running.

The chain of plates is composed of plates of equal length, jointed in such way that the adjacent rows of holes are distant twice the 50 distance between the adjacent rows of holes in the body of each plate, and the punching-out and filling-in mechanisms are so spaced apart that as the chain of plates travels there will be a joint located over each mechanism

at the same time; and in order to bring a row 55 of holes over each we provide mechanism which will move the chain of plates at this time twice the distance it is moved as the bodies of the plates are moved over these punching-out and filling-in mechanisms, and 60 thus it is insured that rows to be punched out and to be filled in will always be opposite the punching-out and filling-in mechanisms. These motions are obtained by means of a 65 disk having pins on opposite faces, and separate cams coöperating with said pins, and suitable transmission devices, as we will proceed now more particularly to describe and finally claim.

In the accompanying drawings, illustrating 70 the invention, in the several figures of which like parts are similarly designated, Figure 1 is an end elevation, and Fig. 2 is a side elevation of sufficient of the block-feeding and splint-cutting portion of a match 75 making machine, it being suggested that the whole machine is constructed to cut and stick the splints, heat, apply the wax, apply the igniting material, dry the matches, and when discharged convey them away or box them. 80 Fig. 3 is a plan view of one of the endless-chain plates, broken out in the middle. Fig. 4 is an edge view of the plate. Fig. 5 is a cross-section of the plate. Fig. 6 is an elevation of the upper cam. Fig. 7 is an elevation 85 of the lower cam. Fig. 8 is a bottom plan view of the pin disk.

The frame 1, the main shaft 2, having pulleys 3 and 4 at opposite ends, and the driving mechanism (not shown) may be as usual. 90

On the main shaft is a gear wheel 5, meshing with a gear wheel 6 on a parallel shaft 7, and this gear wheel 6 meshes with a gear wheel 8 on another parallel shaft 9. On the opposite end of shaft 7 is a cam 10, and on 95 the opposite end of shaft 9 is another cam 11, the pitch of the cam 11 being as two to one with reference to the pitch of cam 10.

12 is a disk, mounted on the end of a shaft 13, which is supported by an arm 14 arranged 100 in a bracket 15, and by an arm 16 projecting from the frame 1. The lower face of the disk 12 is provided with a series of pins or a number of groups of pins 17, and the upper face is provided with as many pins 18 as there are 105 groups of pins on the lower face. The cam 10 engages the pins 17 to turn the disk, and consequently the shaft 13 uniformly step-by-

- step, while the cam 11 coöperates with the pins 18 also to turn the disk and its shaft, and inasmuch as the pitch of the cam 11 is twice that of the cam 10, it follows that the 5 cam 11 by contact with pins 18 will move the disk twice the distance that it is moved by engagement of the cam 10 with one of the pins 17, the purpose of which movement will presently appear.
- 10 The cutting and filling-in mechanism and the punching-out mechanism herein in part illustrated, need not be particularly described since they may be of any approved construction.
- 15 The endless chain of plates is composed of a series of plates 19, substantially like those illustrated in detail in Figs. 3, 4 and 5, wherein the body of the plate is provided with twelve, more or less, rows of holes 20, in 20 which the match splints are stuck by the filling-in mechanism, and then carried from one part of the machine to another as the manufacture of the match progresses. The edges of the plates are provided with toothed-racks 21, and the plates are connected by hinge-joints 22 and 23. The hinge joints are so proportioned that the distance between the last row of holes in one plate and the first row of holes in the next adjacent plate is 25 twice the distance between any other two rows of holes in the body of the plate; and hence, the endless chain of plates, in order to advance from the last row mentioned to the first row mentioned, must be moved twice 30 the distance that the chain is moved in the progression of the rows of holes in the body of any plate. The uniform step-by-step motion is accomplished by the action of the cam 10 upon the pins 17 on the lower face of 35 the disk 12, while the double movement referred to is accomplished by cam 11 acting upon the pins 18.

The described motions of the pin disk are transmitted to the endless chain of plates 40 through the shaft 13, the bevel-gears 24, and the train of gears 25, 26 and 27. The last-mentioned gear 27, is mounted upon a shaft 28, which is provided with mutilated gears 29 which mesh with the racks 21 of the respective plates constituting the chain of 45 plates. The chain of plates is further engaged by mutilated gears 30 on the shaft 31, which supports the gear wheel 25.

Thus, by the construction described, full 50 provision is made for successively placing the rows of holes in position to be filled in by the filling-in mechanism, and simultaneously presenting rows of holes containing finished matches in position for the punching-out 55 mechanism.

As already pointed out, we prefer to time the mechanisms in such way that while the punching-out mechanism on its forward movement is punching out or discharging a 60 row of finished matches, the cutting head of

the filling-in mechanism serves as the filling-in mechanism when on its upward motion; and during the time that the punching-out mechanism is about one-third of the distance on its backward stroke, and the filling-in 70 mechanism is about one-third the distance on its downward stroke, and until these mechanisms reach two-thirds of their forward and upward strokes respectively, the chain of plates is moved forward the length 75 of the distance between the centers of two adjacent rows of holes in the plates, so that the next rows of holes are respectively opposite the punching-out and the filling-in mechanisms and are there securely held until the 80 mechanisms recede.

What we claim is:—

1. In a match making machine, an endless chain of jointed plates, a punching-out mechanism, and a splint-cutting and filling-in 85 mechanism, combined with a rotary pin-disk having pins on one face equal in number to the number of rows of holes in a plate, and a pin on the opposite face arranged to come into position upon the approach of a plate- 90 joint, and separate cams of unequal pitch arranged below and above the pin-disk and co-operating with the pins, respectively to move the endless-chain step-by-step for each row of holes in each plate and twice that distance 95 at each joint.

2. In a match making machine, an endless chain of jointed plates, a punching-out mechanism, and a splint-cutting and filling-in mechanism, combined with a rotary pin-disk 100 having pins on one face equal in number to the number of rows of holes in any number of plates and spaced apart in groups numerically coequal with the rows in each plate, pins on the opposite face located with reference to the 105 joints in the plates, and separate cams of unequal pitch coöperating with the pins on the two faces of the disk and respectively controlling the movement of the chain during the passage of the plates and their joints with 110 reference to the punching-out and filling-in mechanisms.

3. In a match making machine, an endless-chain of jointed plates, toothed racks thereon, mutilated gears engaging said racks, a 115 punching-out mechanism and a filling-in mechanism, combined with a double rotary pin-disk, two cams coöperating with the pins on said disk periodically, and successively, and means to transmit the varied motion 120 from the pin-disk to the mutilated gears.

In testimony whereof we have hereunto set our hands this 8th day of Sept., A. D. 1906.

JAMES H. WEAVER.
ISAAC R. LAUX.
